(57) **CLAIM**

The ornamental design for a mounting bracket and rail for portable tool stand, as shown and described.

DESCRIPTION

FIG. 1 is a perspective view of the mounting brackets and rail of the present invention.

FIG. 2 is a perspective view of the mounting brackets and rail of the present invention.

FIG. 3 is a sectional view of the mounting bracket and rail of the present invention taken along line 3—3 of FIG. 2.

FIG. 4 is a side view of the mounting bracket and rail of the present invention.

FIG. 5 is an end view of the mounting bracket and rail of the present invention; and,

FIG. 6 is a top view of the mounting bracket and rail of the present invention.

The phantom broken lines shown are for illustrative purposes only and form no part of the claimed design. The rail is of indeterminate length.
